EXPANSION PLIERS OR SIMILAR ARTICLE

Thomas C. Flenner, Centerville, Ohio, assignor to The National Cash Register Company, Dayton, Ohio, a corporation of Maryland

Filed Oct. 6, 1965, Ser. No. 87,337

Term of patent 7 years

(Cl. D54—13)

FIG. 1

FIG. 2

FIG. 3

FIG. 4

FIG. 5

FIG. 1 is a top plan view of an expansion pliers or similar article showing my new design;

FIG. 2 is a side elevational view thereof;

FIG. 3 is a fragmentary top plan view of a modified form of the expansion pliers or similar article shown in FIG. 1;

FIG. 4 is a fragmentary top plan view of a further modified form of the expansion pliers or similar article shown in FIG. 1; and

FIG. 5 is a fragmentary top plan view of still a further modified form of the expansion pliers or similar article shown in FIG. 1.

The dominant features of my design reside in the full-line portions of the drawing.

I claim:

The ornamental design for an expansion pliers or similar article, as shown and described.
